UNITED STATES PATENT OFFICE.

ALFRED CHARLES GUNN, OF GENEVA, SWITZERLAND.

STOP-WATCH.

SPECIFICATION forming part of Letters Patent No. 503,416, dated August 15, 1893.

Application filed January 25, 1893. Serial No. 459,636. (No model.)

To all whom it may concern:

Be it known that I, ALFRED CHARLES GUNN, of Geneva, Switzerland, have invented certain new and useful Improvements in Stop-Watches, of which the following is a specification.

The invention consists of a very compendious, strong and easily manufactured mechanism of watches indicating at a glance the time in hours, minutes and seconds, and indicating the measure of a lapse of time varying from one-fifth of a second to twenty-four hours.

In the accompanying drawings, Figure 1 is a face view of my improved stop watch. Fig. 2 is a plan view of the mechanism of my stop watch as seen after the removal of the dial, said mechanism being in a condition of rest. Fig. 3 is a similar plan view of the mechanism at the moment of starting. Fig. 4 is a similar plan view of the mechanism after the setting of the seconds and minutes hands to zero. Fig. 5 shows in a longitudinal section and elevation and an inverted plan the device causing the connection and disconnection of the seconds hand of the stop watch with the movement, and Fig. 5^a is a longitudinal section of the same parts in larger size. Fig. 6 is an elevation of the connecting and disconnecting device of the hands of the minutes and hours indicator, and Fig. 6^a is a longitudinal section and partial elevation of the same parts in larger size. Fig. 7 is a diagram of the train of wheels. Fig. 8 is a section of the rocking piece E and wheels e² and e³.

In all the figures the same letters refer to the same parts.

As shown in Fig. 1 the watch indicates the time on two small dials A and B, the first one giving the hours and minutes and the second one giving the seconds as is usual in watches. A third dial C is intended to indicate the hours and minutes of the stop watch and the circumference of the watch dial bears the divisions of seconds and of one-fifth of seconds which are indicated thereon by the seconds hand D pivoted in the center of the watch.

The mechanism giving the usual time on the dials A and B is composed of the usual train of wheels which are substantially shown in Fig. 7 in which X is the spring barrel gear teeth, and Y' is the pinion of the first wheel Y. Z is an intermediate wheel and W is the

seconds wheel placed in the center of the watch and whose pinion is acted upon by the wheel Z and the wheel W gears with the escapement wheel W' of any system whatever.

The hand setting mechanism which is shown in Figs. 2, 3 and 4 is intended to act upon the hour wheel A', rotating as usual on the axis of the first wheel Y and bearing the hour hand on the dial A.

A² is the usual transmitting wheel causing the minute wheel of said dial A to perform twelve revolutions while the hour hand performs one revolution. The hand setting mechanism is composed of a rocking bridge E pivoted at e and carrying the gear wheels e' e² and e³ which are constantly in gear with one another. The wheel e' is constantly in gear with the crown pinion e⁵. The wheel e² has an axis traversing the rocking bridge E and bearing on the top of the latter another wheel e³ fixed to said tubular axis by means of a screw e⁹. The wheel e³ is generally in gear with the winding up pinion e⁶ by the action of the spring e⁷ upon the bridge E, but when the crown pinion is turned backward the teeth of the wheel e³ as it revolves slip upon the teeth of the wheel e⁶ and raise the rocking bridge E against the yielding action of the spring e⁷ which normally causes the wheel e³ to be in engagement with the wheel e⁶. A push lever F operates the rocking bridge E as shown in Fig. 4 so as to disengage the wheel e³ from the wheel e⁶ and at the same time to bring the wheel e³ into gear with the minute wheel A², and the mechanism is then ready for setting the hands by revolving the stem.

The mainspring barrel X which gears as already stated with the pinion Y' of the wheel Y gears at the same time with a pinion C² fixed to an axis C' on which is fixed with smooth friction a cannon pinion H (Figs. 6 and 6^a) having a sleeve surrounding the axis C'. The said cannon pinion is provided with a spring h bearing with its two upturned arms against the lower face of a cannon disk J having a setting heart piece j and sleeve carrying the minutes hand c' of the indicator. A second cannon wheel K also having a sleeve is placed above the disk J and provided with a heart piece k upon its under side looking toward the heart piece j so that both heart

pieces *k* and *j* are adapted to be simultaneously acted upon by means of one and the same setting lever. The cannon of the wheel *K* carries the hour hand *c*² of the indicator.

5 An intermediate device composed of a pinion gearing with the wheel *K* and a wheel *L* connected with said pinion and gearing with the pinion *H* connects the mechanism of the hands *c*' *c*² causing them to move together, the 10 wheel *K* moving its hand *c*² from one division to another of the dial *C* while the pinion *H* moves its hand *c*' a complete revolution. This intermediate device is pivoted to a rocking lever *L'* which is acted upon by a suitable 15 spring so as to cause said device to engage with the wheel *K* and pinion *H* as just described but which may also be acted upon by the cam *O* so as to disengage said pinion and wheel *L* from said wheel *K* and pinion *H* 20 when the cannon wheel *K* is to be stopped, the pinion *H* being constantly rotating and said pinion *H* being not liable to be stopped when the stop watch is arrested.

The stoppage of the hands *c*' *c*² of the dial 25 *C* is effected by means of the projection *m* of the spring *M* bearing against the edge of the cannon disk *J* and preventing the rotation of the latter together with the wheel *K* and hands *c*' *c*², the spring *h* and pinion *H* being 30 rotated by the axis *C'* and the spring *h* sliding against the under side of said disk *J* instead of operating to rotate the same. The spring *M* is thrown out of reach of the wheel *J* by means of the hammer *N* pivoted at *n* 35 and bearing under the action of a spring *n'* with its arm *n*² against the cam *O*. Said arm *n*² may be engaged more or less into the recesses of the cam *O* as shown in Figs. 2 and 4. The extremity of the hammer *N* may be in 40 the outcut *m'* or against the face *m*² of the spring *M* and according to these two positions the latter either bears with its projection *m* against the disk *J*, as seen in Fig. 3, or is held out of reach of said disk as shown 45 in Figs. 2 and 4. When in the position Fig. 4, its projection *n*³ bears at a time upon the heart pieces *k* and *j* of the indicator, setting the two hands *c*' *c*² simultaneously to zero. The hammer *N* furthermore effects the putting 50 into or out of action of the seconds hand *D* as shown in Fig. 5. The axis *D'* placed in the center of the watch and performing one revolution each minute carries a disk *P* with rugous face, fixed to said axis, and a cannon disk *Q* provided with a rugous under face adjacent to the rugous face of the disk *P*. The 55 cannon of the disk *Q* carries a heart piece *q* and the seconds hand *D*. A spring *R* secured at *r* to the plate has a forked end receiving the cannon 60 of the disk *Q* and said spring normally tends to press the disk *Q* against the disk *P* (see Fig. 5^a), thereby causing the disks *P* and *Q* to rotate together when the spring *R* is in a normal position. This is the case when the hammer *N* 65 which passes beneath said spring *R* is placed between the two projections *r'* and *r*² of the latter (see Figs. 1 and 5^a). If the hammer *N*

is shifted and engaged beneath one or the other of said projections *r'* *r*² (Figs. 3, 4 and 5) the spring *R* is raised and this also raises 70 the disk *Q*, heart piece *q* and hand *D* separating the disks *P* and *Q* from one another preparatory to stopping the hand *D*.

The stopping of the hand *D* is effected by means of the projection *m*³ of the spring *M* 75 being brought to bear against the circumference of the disk *Q* simultaneous with the projection *m* of said spring *M* being brought to bear against the disk *J* as above specified, and this action takes place when the end of the 80 hammer *N* is received in the recess *m'* of the spring *M* as in Fig. 3. The setting to zero of the hand *D* is caused by the hammer *N'* operating upon the heart cam *q*.

S is a spring brake acting upon the cam 85 wheel *O*, and *T* is the usual pushing lever pivoted at *t* and acted upon by a pusher, preferably by the winding stem as shown. Said lever *T* bears a pawl *U* acting upon the teeth of the ratchet cam wheel *O* as is usually the 90 case in stop watches.

The herein described mechanism works as follows: Supposing the cam *O* to be placed as shown in Fig. 2, it is to be seen that the arm *n*² of the hammer *N* is partially engaged in 95 one of the notches of the cam *O* and is placed in its middle position in which it allows the heart pieces *j* and *k* to rotate and raises the spring *M* out of reach of the disks *Q* and *J*. The rocking lever *L'* acted upon by the spring 100 *l* engages its hook in a notch of the cam *O* and thereby causes the wheels of the device *L* to engage with the pinion *H* and wheel *K*. The hand *D* and the indicator hands *c*' and *c*² are therefore going. Now if the cam wheel *O* is 105 rotated one tooth by the pawl *U* the hammer *N* is completely lifted and its extremity moves into the outcut *m'* of the spring *M*; the points *m* and *m*³ of the spring *M* therefore strike both the disks *J* and *Q* and cause the hands 110 *D*, *c*' and *c*² to be stopped. At the same time the rocking lever *L'* is moved away by the cam *O* so as to disengage the device *L* from the pinion *H* and wheel *K* and the spring *R* is 115 lifted by the action of the hammer *N* against the projection *r'* (Fig. 5) whereby the disk *Q* is disengaged from the disk *P*. If the cam wheel *O* is again rotated one tooth by means of the push lever and pawl, the arm *n*² is fully 120 engaged in one of its notches. Thereby the spring *M* is lifted; the rocking lever *L'* remains lifted or moved away and the spring *R* also, the hammer *N* striking the projection *r*² as soon as it has left the projection *r'* when 125 passing from the position of Fig. 3 to that of Fig. 4; the disk *Q* can therefore be duly rotated to set the hand *D* to zero, when the hammer *N'* strikes the heart piece *q*. At a new pressure of the pusher the hands *D* *c*' and *c*² are again started as described above with reference to Fig. 2.

I claim as my invention—

1. In a stop watch, the combination with the push lever, pawl and cam wheel, of a hammer

N, a spring R having downward projections r', r^2 on its under side adapted to be acted upon by the hammer N in its extreme movements, the arbor D' and friction disk P upon 5 said arbor, a sleeve around said arbor and the disk Q and the seconds hand D connected therewith, said spring R maintaining contact between the disks P and Q and the hammer N raising said spring to separate said disks, substantially as and for the purposes set forth.

2. In a stop watch, the combination with the push lever, pawl and cam wheel, the auxiliary dial and its hands $c' c^2$ and the independent seconds hand D, of the hammer or lever N, 15 the spring M having projections $m m^3$ and a concave portion M', the disks Q and J upon the arbors of said hands and having roughened edges adapted to be engaged and their rotation arrested by the aforesaid projections 20 $m m^3$ and the hands stopped when the end of the hammer N is moved into the concave por-

tion m' , substantially as and for the purposes set forth.

3. In a stop watch, the combination with the auxiliary dial C and its hands $c' c^2$, the pusher, 25 pawl and cam wheel, of the arbor C', the pinions C² and H on the arbor C', the spring h, the disk J and heart cam j and their tubular arbor carrying the minute hand c', the toothed wheel K and heart cam k and their tubular 30 arbor carrying the hand c², means for stopping and releasing the disk J, gears and means for moving the same into or out of contact with the pinion H and wheel K, substantially as and for the purposes set forth.

In testimony whereof I have signed my name to this specification in the presence of two subscribing witnesses.

ALFRED CHARLES GUNN.
